UNITED STATES PATENT OFFICE

RAY W. JONES AND THEODORE R. MILLER, OF HUTCHINSON, KANSAS

DESIGN FOR A DISPLAY ADVERTISING BOARD

Application filed March 27, 1933. Serial No. 47,611. Term of patent 7 years.

To all whom it may concern:

Be it known that we, RAY W. JONES and THEODORE R. MILLER, citizens of the United States, residing at Hutchinson, Reno County, Kansas, have invented a new, original, and ornamental Design for a Display Advertising Board, of which the following is a specification, reference being had to the accompanying drawing forming a part thereof.

In the drawing:—

play advertising board showing our new design.

Figure 2 represents a side elevation of a display advertising board showing our new design.

We claim:—

The ornamental design for a display advertising board as shown.

RAY W. JONES.
THEODORE R. MILLER.
